(57) **CLAIM**

The ornamental design for a cleaning robot, as shown and described.

DESCRIPTION

1. Cleaning robot
2. Cleaning robot
3. Cleaning robot
4. Cleaning robot

- 1.1** : Front
- 1.2** : Back
- 1.3** : Left
- 1.4** : Right
- 1.5** : Top
- 1.6** : Bottom
- 1.7** : Perspective

- 2.1** : Front
- 2.2** : Back
- 2.3** : Left
- 2.4** : Right
- 2.5** : Top
- 2.6** : Bottom
- 2.7** : Perspective

- 3.1** : Front
- 3.2** : Back
- 3.3** : Left
- 3.4** : Right
- 3.5** : Top
- 3.6** : Bottom
- 3.7** : Perspective

- 4.1** : Front
- 4.2** : Back
- 4.3** : Left
- 4.4** : Right
- 4.5** : Top
- 4.6** : Bottom
- 4.7** : Perspective

Figs. 1.1-1.7 are drawings showing a first embodiment of the cleaning robot; figs. 2.1-2.7 are drawings showing a second embodiment of the cleaning robot; figs. 3.1-3.7 are drawings

(Continued)

showing a third embodiment of the cleaning robot; and figs. 4.1-4.7 are drawings showing a fourth embodiment of the cleaning robot; the present product is used for cleaning the floor/ground. The portions of the cleaning robot each shown with gray color overlay and located between two broken-line boundaries form no part of the claimed design.
